UNITED STATES PATENT OFFICE.

JOSEPH E. PERRAULT, OF WATERTOWN, MASSACHUSETTS, ASSIGNOR TO HOOD RUBBER COMPANY, OF WATERTOWN, MASSACHUSETTS, A CORPORATION OF MASSACHUSETTS.

METHOD OF MAKING ACIDPROOF CONTAINERS.

Application filed February 10, 1922. Serial No. 535,645.

To all whom it may concern:

Be it known that I, JOSEPH E. PERRAULT, a citizen of the United States, and a resident of Watertown, in the county of Middlesex 5 and State of Massachusetts, have invented certain new and useful Improvements in Methods of Making Acidproof Containers, of which the following is a specification.

My present invention relates to improvements in methods of and apparatus for making acid proof containers of vulcanizable material such as rubber compound, and aims to provide a simple economical and efficient process and apparatus for carrying out the same whereby containers free from blisters may be secured without the use of completely closed molds such as have heretofore been regarded as necessary.

The apparatus referred to is shown in the accompanying drawing in which—

Fig. 1 is a sectional view of a core and applied presser device or former, and Fig. 2 is a perspective view of the former and fabric or fibrous layer.

25 In practising my invention, I use a core or mandrel 1 of a shape conforming to that of the desired article, which is preferably of a slightly tapered formation in part, at least the part towards the bottom. To the 30 bottom and sides of this mandrel is applied the bottom and side (including end) wall forming material 2, in the shape of sheets of rubber compound, which is rolled down in the customary manner. The said bottom 35 and sides are then preferably covered by a layer of cloth or other suitable fibrous material, indicated at 3, and this cloth is pressed against the container and vulcanized, while so pressed, in an open heat in the manner 40 well understood by those skilled in the art. A convenient manner of so pressing the fabric is to make the core tapered and provide a correspondingly tapered presser member 4 which, when the core is supported in inverted position will, by its own weight, hold the fabric pressed against the surfaces due to the tapered formation.

I have discovered that the blisters which cause defects in such containers, occur practically exclusively in the bottom and side walls adjacent thereto and that it is necessary only to have the presser member cover the bottom and part of the sides adjacent thereto as shown.

55 The fabric applies the pressure smoothly

to the container and yet affords means for venting the gases.

The fabric layer may be placed in the channel of the presser member as shown in Fig. 2, and the assembly applied to the container.

Having thus described my invention, what I claim is:—

1. The herein described method of making rubber acid proof containers, and the like which consists in applying sheet rubber to a mandrel or core to form the bottom and sides, applying over the bottom and two of the sides a fibrous layer, and vulcanizing the article in an open heat while pressing said fabric against the said bottom and sides.

2. The herein described method of forming acid proof containers and the like which consists in applying sheet rubber to a suitable mandrel or core to form the bottom and sides, supporting said mandrel to hold the container in inverted position, applying to the bottom and portions of the side surfaces a covering of fibrous material and vulcanizing the article in open heat while said fibrous covering is pressed against the said surfaces.

3. The herein described method of making acid proof containers and the like which consists in applying bottom and side forming layers of sheet rubber to a tapered core, applying a fibrous covering to the bottom and side surfaces, supporting the mandrel with the container in inverted position, and applying thereto a weighted tapered channel shaped presser member.

4. The herein described method of making acid proof containers which consists in applying sheet rubber material to a suitable core and applying pressure to the bottom and adjacent portion of the side walls, and vulcanizing the article in open heat while such pressure is maintained and while venting the surface to which such pressure is applied.

5. The herein described method of making acid proof containers which consists in applying sheet rubber material to a suitable core and applying pressure to the bottom and adjacent portion of the side walls by a weight member, and vulcanizing the article in open heat while such pressure is maintained and while venting the surface to which such pressure is applied.

In testimony whereof, I affix my signature.

JOSEPH E. PERRAULT.
